SOCKET WRENCH TURNING DEVICE

Loren A. Ross, Richmond, Calif.

Application May 22, 1950, Serial No. 163,479

2 Claims. (Cl. 81—177)

1

The present invention relates to improvements in a socket wrench turning device. It consists of the combinations, constructions, and arrangement of parts, as hereinafter described and claimed.

In the automotive art, it is a conventional practice to employ studs for removably securing the wheels in place. These studs are difficult to remove, especially from the heavier types of wheels, due to rusting of the studs and accumulation of corrosive substances thereon. Moreover, these studs must be applied tightly; consequently, considerable force must be used in removing the studs.

Socket wrenches are employed for removing these studs, and mechanics often insert a length of pipe through an opening in the wrench in order to obtain the necessary leverage. However, the pipe bends frequently before the stud will loosen.

Accordingly, an object of my invention is to provide a turning device, which may be applied readily to a socket wrench, and utilized for imparting the necessary rotary force to the wrench for loosening wheel studs, or the like.

More specifically stated, I make use of a rod, which is adapted to be inserted into an opening formed in the socket wrench. This rod has one end of a chain anchored thereto. The chain has sufficient length so that it may be wrapped around the wrench until the chain overlaps itself, with the links in the outer section of the chain stacked upon the links in the inner section of the chain. The outermost links will serve to retain the rod in the wrench opening when endwise pull is exerted upon the free end of the chain to loosen the stud.

Other objects and advantages will appear as the specification continues. The novel features of the invention will be pointed out in the claims hereunto appended.

Drawing

For a better understanding of my invention, reference should be had to the accompanying drawing, forming part of this application, in which:

Figure 1 is an elevational view of my turning device operatively applied around a socket wrench, the view being taken from the plane I—I of Figure 2;

Figures 2, 3 and 4 are sectional views taken along the lines II—II, III—III and IV—IV, respectively, of Figure 1;

Figure 5 is a perspective view of the foldable standard, illustrating the sections thereof partially folded;

Figure 6 is a fragmentary end elevational view of the standard; and

Figure 7 is a side elevational view of a socket wrench, with one end thereof engaging the stud of a wheel, while the opposite end of the wrench is rotatably sustained by the standard.

While I have shown only the preferred form of my invention, it should be understood that various changes, or modifications, may be made within the scope of the annexed claims without departing from the spirit thereof.

Detailed description

Referring to the drawing in detail, I have disclosed a conventional socket wrench indicated generally at A. This wrench includes the usual shank 10 having enlarged heads 11 and 12 fashioned on opposite ends thereof, in which non-circular sockets 14 and 15, respectively, are provided. As illustrated, the socket 14 is hexagonal, while the socket 15 is squared. Transverse rod-receiving openings 16 and 17 are formed in the heads 11 and 12, respectively.

In Figures 1 to 3, inclusive, I show a chain designated B. This chain is made up from a plurality of sets of links 18, which are interconnected by chain pins 19. As illustrated in Figure 1, the chain has sufficient length for wrapping around the heads 11 or 12 until the chain overlaps itself. When thus wrapped, the links in the outer section B1 will be stacked upon the links in the inner section B2 of the chain.

The innermost pair of links has a wrench-engaging rod 20 swingably secured thereto by a pin 19a. This rod is adapted to be inserted endwise into the opening 16 or 17, depending upon which head of the wrench the chain is intended to be wrapped. It will be noted that the outer section B1 of the chain will hold the rod 20 from becoming disengaged from the wrench opening into which it has been inserted, when the chain is drawn endwise (see Figure 1). The outer pivoted end 20a of the rod 20 is confined between the links to which it is attached; and, accordingly, will not offer any obstruction to wrapping the outer section of the chain upon the inner section.

For the purpose of drawing the chain tightly around the wrench and turning the latter, I provide a handle C. The handle may be secured to the outermost end links of the chain by a pin 21, and extends in prolongation with respect to the chain. Rollers 22 surround the pins 19 and space the links in each pair apart.

As illustrated in Figures 2 and 7, studs 23 are

provided in the regular manner for securing the wheel D in place. These studs have been shown as having hexagonal heads adapted to be received by the correspondingly-shaped socket 14. In the event that squared heads are provided on the studs, the socket 15 is used for engaging with such heads.

It will be realized, of course, that considerable torque must be applied to the wrench when loosening the studs. For this reason, I have provided a standard indicated generally at E, which is used as a prop under the outermost end of the wrench (see Figure 7).

The standard E includes upper and lower sections 24 and 25, respectively, which are connected together by a hinge 26 disposed at one side of the standard. When in extended position, as shown in Figure 7, the upper section rests on the top of the lower section. Any suitable means may be employed for retaining the sections 24 and 25 in aligned relation with one another when the standard is extended. For this purpose, I have shown a hooked catch 27, which is pivoted by a screw 28 to the upper section 24. The hook 29 of this catch is adapted to engage with a headed screw 30 projecting from the lower section 25.

It is quite apparent that disengagement of the hook 29 from the screw 30 will permit the two sections of the standard E to be folded upon one another. This will allow the standard to be stored in a relatively small space.

Upon extending the standard sections, as in Figure 7, the lower section 25 is adapted to rest directly upon the ground 31, or other surface. The upper section 24 has a series of steps 32 fashioned therein, which define curved seats 33 arranged one above the other.

In Figure 7, I show the head 12 of the socket wrench A resting on one of the seats 33 so as to rotatably support the outer end of the wrench, while the socket 14 at the opposite end of the wrench is engaging with the head of a stud 23. These studs, of course, are arranged in a circle about the axis 34 in the usual manner. The particular step selected on the standard for supporting the outermost end of the wrench depends upon the elevation of the stud being engaged above the ground 31, in order to sustain the wrench in horizontal position. Obviously, when the wrench is turned end-for-end, its head 11 can be supported by the standard.

Summary of operation

The operation of my socket wrench turning device is summarized briefly as follows:

Assuming that the studs 23 to be removed have hexagonal heads, the socket wrench A is moved endwise until the socket 14 telescopes over the selected stud head. The standard E is positioned at the outermost end of the applied wrench, with the head 12 resting in one of the curved seats 33 and the wrench mounted horizontally.

Now the mechanic inserts the rod 20 into the transverse opening 16 of the wrench. The chain B is wrapped around the head 11 in the manner shown in Figure 1 until the chain overlaps itself.

At this time, the links 18 of the outer section B1 of the chain will be stacked upon the links of the inner chain section B2. This will retain the rod 20 in the opening 16 when the mechanic moves the handle C in the direction of the arrow 35 in Figure 1 to loosen the engaged stud. Successive studs are removed in the same manner, the outermost end of the wrench A being supported for rotation in one of the curved seats 33 of the standard E in each case. If desired, a pipe 36 may be telescoped over the handle C (see Figure 7) to give additional leverage.

I claim:

1. In a socket wrench turning device: a chain, including a plurality of links swingably connected together; a rod secured to one end of the chain, and made for insertion into a transverse opening in a socket wrench; the chain having sufficient length so that it may be wrapped around the wrench until the chain overlaps itself, with links in an outer section of the chain stacked upon links in an inner section thereof; the outer section of chain overlying the rod to retain the rod from dislodgement from the wrench opening; and a lever handle secured to the outermost end of the chain.

2. In a socket wrench turning device: a chain, including a plurality of links swingably connected together; a straight rod having an end thereof secured to links at one end of the chain; the full length of the rod beyond the chain being made for insertion into a transverse opening in a socket wrench; the chain having sufficient length so that it may be wrapped around the wrench until the chain overlaps itself, with links in an outer section of the chain stacked upon links in an inner section thereof; the outer section of chain overlying the rod to retain the rod from dislodgement from the wrench opening; the swingably-secured end of the rod being confined below outermost longitudinal edges of the links to which it is attached, when the chain is wrapped around the wrench, so that this rod end will be positioned underneath said link edges and will not offer any obstruction to wrapping the outer section of the chain upon and against the inner chain section; and a lever handle secured to the outermost free end of the chain.
